UNITED STATES PATENT OFFICE.

ERNEST NELSON HUMPHREY, OF NEW BRITAIN, CONNECTICUT, ASSIGNOR TO UNITED ROYALTIES CORPORATION, OF NEW YORK, N. Y.

BEATER.

Application filed March 12, 1926. Serial No. 94,193.

This invention relates to improvements in beaters which is particularly intended for use as an egg beater and the like.

This invention relates to certain improvements in the supporting frame, whereby it is made rigid, and so constructed to prevent the beater pinions becoming disengaged from the operating wheel.

The object of the present invention is to 10 form a bridge integral with the supporting frame, said bridge extending under but adjacent the pinions, whereby the pinions are prevented in transit, or in operation, from becoming disengaged from the operating 15 wheel.

In the accompanying drawings:

Figure 1 is a side elevation of a beater which embodies my present improvement.

Fig. 2 is a view of the upper end of the 20 beater taken at right angles to Fig. 1.

Fig. 3 is a top plan view of the supporting frame.

Fig. 4 is a horizontal sectional view taken 25 through the lower part of the supporting frame.

Fig. 5 is a reduced plan view showing the blank out of which the supporting frame with its integral bridge is formed.

In the type of beater here shown, there 30 are two beaters 1 and 2, which extend parallel to each other and have their outwardly bulged portions 3 interlocking. This form of beater is provided with a substantially U-shaped wire member 4, which passes 35 through the lower ends of the bulged portion 3 of the blades, and through pinions 5, which are attached to the upper ends of the beater blades 1 and 2.

The present improvement pertains to the 40 supporting frame, which consists of a vertically formed portion 6, its lower end being bent into substantially a U-shape 7. Attached to the vertical portion or arm 6 of the frame is an operating gear wheel 8, to which 45 is attached a suitable operating handle 9. The teeth 10 of the operating wheel 8 extend between the pinions 5 and engage both of them, whereby the operation of the wheel 8 causes the two beater blades 1 and 2 to 50 revolve in opposite directions. Thus far, I have described the ordinary construction of this type of beaters.

One improvement of this application is to 55 form a bridge 11 in the lower portion of the U-shaped part 7. This bridge is integral

with the horizontal portions of the U-shaped part 7, and as shown in Figs. 1 and 2, the bridge is located under the pinions 5, but adjacent thereto, whereby the pinions cannot be moved downward to cause them to 60 disengage the teeth 10 of the operating wheel 8. The additional function of this bridge portion is to afford rigidity to the U-shaped bent portion 7, of the supporting frame, whereby it is held more firmly 65 against being bent in transportation or otherwise.

It is the primary object of the present invention to make the beater as rigid as possible, and at the same time prevent the pinions from becoming disengaged with the 70 teeth 10 of the operating wheel.

The pinions 5 can become disengaged should some part of the beater blades 1 and 2 be bent in a manner to shorten them, 75 thus pulling the pinions attached to their upper ends downward, which would either cause the pinion to disengage the teeth 10, or be in such a position that it would not 80 properly operate. This is impossible with the integral bridge herein described.

The supporting frame is stamped from sheet-metal, in a manner to form the bridge 11, after which the supporting frame is bent to the shape shown in the accompanying 85 drawings.

The upper ends 12 of the rod 4, are attached to the sides 13 of the U-shaped part of the supporting frame in any desired 90 manner, as the manner of attaching the wires forms no part of my present improvement.

The handle 14 may be attached to the arm 6 of the supporting frame in the manner here shown, or in any desired way, since 95 that forms no part of the present improvement.

It is highly desirable to form a supporting frame which is rigid and which prevents the disengagement of the pinions from the operating gear wheel, as herein described. It is found that a supporting frame constructed as defined herein is very rigid and is a desirable practical improvement over the frames heretofore constructed.

I am aware of the construction of a bridge which is made of a separate part, and which has its ends attached to the supporting frame, for instance, as shown in a 110

co-pending application of Lee E. Earle, Serial Number 31,651, assigned to the United Royalties Corporation. This separate bridge construction, as shown in that application, does not make the supporting frame rigid, and it is expensive to construct and to attach it, after it has been constructed, to the supporting frame.

In the present improvement there is practically no additional expense, because the supporting frame is stamped from sheet-metal with the integral bridge 11, whereby it does not require an additional stamping operation, and when the frame is completed, it adds much rigidity to that part of the beater which supports the beater blades, which is the point where the strain comes.

By reference to Fig. 5, which is a reduced plan view of the blank for the supporting frame, it will be observed that the blank has one end provided with parallel openings 15, forming between them the above-mentioned integral bridge 11.

Having thus described my invention, what I claim and desire to secure by Letters Patent is:

1. A beater comprising a supporting frame having its lower end substantially U-shaped, the horizontal portion of the U-shape having longitudinal openings at each side of its center, the inner sides of the openings curved inwardly forming an integral bridge with a reduced central portion, and enlarged end portions, for the purpose described. 35

2. A beater comprising a supporting frame having its lower end enlarged and substantially U-shaped, the horizontal portion of the U-shape having openings which extend up into the vertical portions of the U-shape, and the horizontal portion provided with an integral longitudinal bridge, for the purpose described. 40

In testimony whereof I hereunto affix my signature.

ERNEST NELSON HUMPHREY.
